(57) **CLAIM**

The ornamental design for an eye shield, as shown and described.

DESCRIPTION

FIG. 1 is a perspective view of an eye shield of our new design.

FIG. 2 is a frontal view thereof.

FIG. 3 is a rear view thereof.

FIG. 4 is a top view thereof.

FIG. 5 is a bottom view thereof.

FIG. 6 is a left side view thereof;

FIG. 7 is a right side view thereof; and,

FIG. 8 is an exploded view thereof.

The broken lines in the drawings are included for the purpose of illustrating unclaimed features and form no part of the claimed design.

The broken lines in the drawings illustrate the unclaimed features of the eye shield and form no part of the claimed design.

1 Claim, 6 Drawing Sheets
